Primary Examiner — Austin Murphy*(74) Attorney, Agent, or Firm* — Grandview Law(57) **CLAIM**

The ornamental design for a station for portable electronic computing devices, as shown and described.

DESCRIPTION

FIG. 1 is a top perspective view of a station for portable electronic computing devices showing my new design.

FIG. 2 is a top plan view thereof.

FIG. 3 is a bottom plan view thereof.

FIG. 4 is a right elevational view thereof.

FIG. 5 is a left elevational view thereof.

FIG. 6 is a front elevational view thereof; and,

FIG. 7 is a rear elevational view thereof.

The broken lines in the figures depict features of the station for portable electronic computing devices that form no part of the claimed design.
